UNITED STATES PATENT OFFICE.

PETER C. FREESE, OF CAYUGA, NEW YORK.

VEHICLE-SPRING.

SPECIFICATION forming part of Letters Patent No. 227,512, dated May 11, 1880.

Application filed February 28, 1880.

To all whom it may concern:

Be it known that I, PETER C. FREESE, of Cayuga, in the county of Cayuga and State of New York, have invented a new Improvement 5 in Wagon and Carriage Frames, of which the following is a specification.

This invention relates to an improvement in wagon and carriage frames so arranged as to be simple in construction and effective in use.

10 The invention consists of two triangular frames, upon which the body of the carriage or wagon rests, and each of the frames has a ring at the point, and through these rings a stirrup passes, this stirrup being at the end of 15 a rod adjustably secured to the under side of the seat, which rests on springs, so that the seat rests entirely upon the springs, whereas the body of the wagon or carriage is only partially supported by them, as will be herein- 20 after more fully described.

In the accompanying drawings, Figure 1 represents a longitudinal sectional elevation, 25 on the line x x , Fig. 2, of a buggy provided with my improvement. Fig. 2 is a view of the under side of the same.

The body or floor A of the buggy or wagon is provided with side springs, B B, upon which the seat C rests at such a height above the floor A as to be convenient for the person occupying the said seat. A bracket, D, is attached to the bottom of the seat C, and through this bracket a rod, E, provided at its upper end with a screw-thread and terminating in a stirrup, F, passes, and is held by a thumb-screw, G. The floor A of the buggy is provided with an aperture, H, to let the rod E pass through. The body-sills I I are hinged, by means of the rings K K, on two triangular frames, J J, formed by the bearing-bars M M 30 and the axles N N of the buggy, and having the points adjoining to each other. A ring, L L, 35

is fastened to each triangular frame J at the point, and both of these rings are linked with the stirrup F. The springs can be arranged parallel with the seat or in any other similar 45 manner.

The box of the buggy will be made outside of the springs, so that the seat and top are entirely supported by the springs, and a load 50 can be carried on the floor, which does not affect the springs.

For box-wagons the end springs are placed onto the bearing-bars M M, as usual, and the rod E is fastened to the bottom of the floor instead of the seat.

According to the load taken on, the springs can be adjusted by the thumb-screw G and the rod E, or by means of a strap and buckle. If a light load is taken on the seat, the springs are allowed to expand as far as they can; but 60 if a heavy load is taken the thumb-screw G is turned down as far as may be necessary.

The within-described device will be found to be of the greatest service on rough roads, for the bearings of the sills I I are not over the 65 axles N N, and if a pressure is brought to act on the bearing-bars directly under the sills I I the rod E will be drawn down and the resistance of the spring will weaken the shock.

Having thus described my invention, what I 70 claim as new, and desire to secure by Letters Patent, is—

The combination, with the two triangular frames having rings at each adjacent point of the rod E, passing through said rings and adjustably secured to a spring-supported seat, as 75 shown and described.

PETER C. FREESE.
